UNITED STATES PATENT OFFICE.

RUDOLPH E. TOLLNER, OF NEW YORK, N. Y.

TOOTHBRUSH COVER DEVICE.

Application filed July 15, 1924. Serial No. 726,198.

This invention relates to a device to be used for covering toothbrushes when not in use.

An object of the invention is to provide a simple and efficient means whereby a toothbrush can be covered when not in use so as to protect it from dust, dirt and other elements which might tend to impair the quality of the bristles.

Another object concerns the provision of simple and efficient means whereby the brush can be kept in a hand-bag or a suitcase in close proximity to other articles without any liability of any moisture on the brush damaging such other articles.

A further object concerns the provision of simple and efficient means whereby the cover for the brush is more or less permanently attached to the brush itself but, nevertheless, can be very easily manipulated to uncover the brush for use.

A still further object concerns the provision of simple and efficient means whereby almost any standard type of brush can be slightly altered in construction to adapt it for use in connection with the cover device.

The invention is illustrated in the drawings, of which—

Figure 1 is a side elevation of the device showing the toothbrush covered;

Fig. 2 is a side elevation partly in section showing the covering case withdrawn and latched in the inoperative position; and

Fig. 3 is a section taken on the line 3—3 of Fig. 1.

The form of the invention shown in the drawings is a preferred form, although it is understood that modifications in the construction and arrangement of the parts and in the character of the materials used may be adopted without departing from the spirit of the invention as set forth in the appended claims.

In its general aspect the invention comprises a toothbrush having a handle. Mounted on the handle is a member which acts as a cover for the brush bristles, and this cover member or element is adapted to be disposed in an operative position over the bristles and can be easily moved, preferably in association with the handle, to an inoperative position, in which position the bristles are uncovered and the brush can be used as in the ordinary manner.

Preferably the cover member is provided with means to engage a portion of the han-

dle for slidable movement, and latch means are provided to hold the cover both in its operative and in its inoperative positions.

The cover member can be easily moved from the operative to the inoperative position, and when it is moved to the inoperative position it is automatically latched in this position, from which position it can be readily unlatched.

The preferred form of the invention is shown in the drawings, in which 1 represents the bristles of the brush and 2 represents the handle. This handle is preferably provided with lateral grooves 3 and 4 extending along the sides thereof. The cover member 5 is in the form of a metallic casing having inwardly projecting flanges 6 and 7 which engage in the above-mentioned grooves. This cover member is provided with straps 8 and 9 which extend around the handle to hold the cover member thereon in its sliding movement. The cover member or casing is provided within its rear open end with a partition 10, which is rigid, and a front wall 11, which is pivoted at 12 and is acted on by a spring 13 which tends normally to hold the pivoted wall 11 in its closed position.

The handle 2 at its rear end is provided in its underface, with a spring latch member 14 having a groove 15 in which a notch in the upper edge of the partition 10 of the cover 5 tends to engage. A stop pin 15^a is disposed on the handle at this point and engages with the rear face of the partition 10 to prevent the cover from over-riding the groove 15. The rear end of this latch member is turned up in a finger 16 permitting the hand of the operator to disengage the latch member easily.

In the operation of the device, assuming the parts are in the position shown in Fig. 1, it will be observed that it is an easy matter to grasp the cover 5 and move it from the position shown toward the rear end of the handle 2. As it reaches this end the partition 10 will engage and move along the inclined face of the latch member 14 and will spring into the groove 15, the front wall 11 being held against the handle by spring 12, thus holding the cover 5 in the retracted position. By reason of the pivoted disposition of the front end plate or wall 11, this will be moved outwardly to permit it to clear the bristles in this rearward movement of the cover 5. In returning the casing to

the operative position the front wall or lid 11 is held open by the hand and the casing moved forward after the hand of the operator has depressed the latch 14 by depressing 5 the finger 16. As soon as the cover casing 5 gets back to the operative position as a cover the pivoted front wall or lid 11 can be released and the spring 13 will force it into the position shown in Fig. 1, wherein 10 it moves to closed position to substantially enclose the bristles and keep them from contact with other articles and also prevent dust and dirt from getting in contact therewith.

It will be noted that with the member 15 5 in the position illustrated in Fig. 2, that this cover constitutes a substantial and comfortable hand-hold for ready manipulation of the brush as in service.

It will thus be seen that I have provided 20 a simple and efficient means for protecting the bristles of a toothbrush when not in use, and which is capable of being readily moved to an inoperative position to expose the bristles. The parts of this device are simple 25 and economical to manufacture and are such as would not tend very easily to get out of order.

What I claim is:—

1. A device of the character described, comprising a handle and brush head, said 30 handle and head having longitudinal grooves in their opposite sides, a spring latch bar having a groove and an end releasing finger, said latch set in the under side of said handle adjacent its rear end, a box like open end 35 casing adapted to enclose said brush head and having inturned top flanges slidably engaging said longitudinal grooves, a rigid partition mounted within the rear open end of the casing and adapted to be engaged by 40 the latch bar to lock the casing on the handle, a pivoted front wall or lid at the front end of the casing, a spring mounted on the casing and bearing against the lid holding the same closed when the casing encloses the brush 45 head, and urging the lid frictionally against the handle when the casing is in uncovering position, and straps extending around the handle and integral with the casing.

2. The device as set forth in claim 1, characterized by a stop pin projecting from the under face of the brush handle adjacent its rear end and adapted to engage the rear face of the partition to prevent the casing from overriding the latch bar groove.

RUDOLPH E. TOLLNER.
